UNITED STATES PATENT OFFICE.

ALONZO WILTON WHITCOMB, OF WORCESTER, MASSACHUSETTS.

ARC LAMP.

SPECIFICATION forming part of Letters Patent No. 443,557, dated December 30, 1890.

Application filed March 27, 1890. Serial No. 345,559. (No model.)

To all whom it may concern:

Be it known that I, ALONZO WILTON WHITCOMB, a citizen of the United States, residing in Worcester, in the county of Worcester and 5 State of Massachusetts, have invented certain new and useful Improvements in Arc Lamps, of which the following is a specification.

My invention relates to improvements in the arc-regulating mechanism of that class of 10 arc lamps in which the upper carbon is lifted to strike the arc by means of the action of an electro-magnet in the main circuit and is fed downward by the action of gravity controlled by gearing.

15 My invention consists in the construction and combination of parts, as hereinafter described and claimed.

In the drawing the figure is a side elevation of so much of the lamp as is necessary to illustrate my invention.

20 The rod C, carrying the upper carbon, has a free vertical movement in the frame and is provided with a rack K. At F, in bearings carried by the lamp-frame, is swung a frame F, supporting a train of gearing. Of this train the pinion 1 meshes with rack K, and carries on its shaft gear 2, meshing with pinion 3, which is on one shaft with gear 4. The shaft of the latter forms the pivoted point T of the 25 frame. Meshing with gear 4 is the pinion 5, on the shaft of which is the flier 6. It will be understood, of course, that the pinion 5 is out of the plane of the rack K, so as not to engage said rack at any position of the frame. 30 The lower extension W of the frame carries the armature R of the arc-striking magnet A, and a stop N is provided for the extension M to rest against when there is no current.

35 M is a magnet connected in series with the arc and acts on lever m, carrying armature m' and fulcrumed at m². A spring m³ acts to return lever m, and a hook m⁴ at the end of the lever engages flier 6 when the latter is raised by the action of magnet A, swinging 40 the frame F.

45 S is a shunt-magnet connected in parallel with the arc and acts on lever s, carrying armature s' and fulcrumed at s². A spring s³ acts to return lever s, and a hook s⁴ at the end 50 of the lever is adapted to engage the flier 6. These two levers M and S have limiting-stops m⁵ and s⁵, respectively.

The conductors and connections for the current are shown at x.

The operation is as follows: On starting the 55 current the magnet A attracts armature R, swings frame F, and the pinion 1 lifts rod C, thus striking the arc. The instantaneous lifting of the pinion 1 and the flier and the inertia of the train of gears causes a positive lifting 60 of the rod C, and the immediate engagement of one of the teeth of the flier with hook m⁴ prevents any possible turning of the gears and pinions, and as long as the current flows the frame F remains stationary, being held by 65 magnet A. The spring m³ is adjusted so that if the current is more than normal the lever m remains with its point or hook m⁴ in engagement with the flier and prevents feed, and when normal the spring causes the hook 70 to rise from the flier and allow the rod C to slowly descend by gravity. The spring s³ is so adjusted that if the arc is too short the hook s⁴ of lever s engages the flier and prevents feed.

75 If the current is insufficient for the space by which the carbons are at any time separated, it is also insufficient to keep hook m⁴ down, and therefore a feed is allowed until an arc of the right length is formed, the hook 80 s⁴ meanwhile being kept out of engagement by means of the current passing through the shunt-circuit, and if the current is excessive or abnormal the hook m⁴ is kept in engagement with flier 6 until the burning of the 85 carbons has increased the arc to a degree proportionate to the current. Therefore it will be seen that unless the current and the arc are of the proper strength and length, respectively, no feed takes place until they become 90 rectified. The effect of this in two or more lamps connected in series across incandescent mains is to maintain equal arcs and arcs of the right length. If the shunt-magnet and its brake s⁴ only were used, the two lamps 95 would have equal arcs; but the length of the arcs would not be regulated; and if only the main magnet M and its brake m⁴ were used the sum of the two arcs might be right; but they would not reliably equal each other.

100 My improved arrangement necessitates equal arcs and correct as well as constant current at all times after the proper current has once been obtained.

Having now described my invention, what I claim, and desire to secure by Letters Patent, is—

- 5 1. In an arc lamp, the combination, with
are striking and feeding mechanism, of two
releasing devices for the feeding mechanism,
one operated by the main current and the
other by a shunt-current and each independ-
ent of the other, substantially as described.
- 10 2. In an arc lamp, the combination, with
are-striking mechanism and a magnet in the
main circuit for operating it, of a second mag-

net in the same circuit and feed-releasing
mechanism operated by said second magnet
and another magnet in the shunt-circuit and
feed-releasing mechanism operated by it, sub-
stantially as described. 15

In witness whereof I have hereunto signed
my name in the presence of two subscribing
witnesses.

ALONZO WILTON WHITCOMB.
